SPRING CLIP

Cecelia F. Wagner and William J. Farrell,
San Francisco, Calif.

Application October 4, 1949, Serial No. 119,448

3 Claims. (Cl. 24—81)

1

This invention relates to spring clips, and more particularly to spring clips formed of wire stock.

A main object of the invention is to provide a novel and improved spring clip which is simple in construction, which is formed from a single piece of wire, and which may be employed for a wide variety of uses.

A further object of the invention is to provide an improved spring clip formed of a single piece of wire, said clip being very inexpensive to manufacture, being neat in appearance, being easy to manipulate, and being adapted to connect a plurality of sheets of material together in overlapped relation in any one of several different ways.

A still further object of the invention is to provide an improved spring clip made from a single piece of wire which may be employed as a package-tie device.

Further objects and advantages of the invention will become apparent from the following description and claims, and from the accompanying drawings, wherein:

Figure 1 is a front elevational view of a spring clip constructed in accordance with the present invention, showing a plurality of pieces of paper secured to said spring clip;

Figure 2 is a rear elevational view of the structure shown in Figure 1;

Figure 3 is a view showing a modified form of spring clip constructed in accordance with the present invention;

Figure 4 is an elevational view showing a still further modification of the spring clip of the present invention;

Figure 5 is an elevational view showing a further modification of the spring clip of the present invention;

Figure 6 is an elevational view showing still another modification of the spring clip of the present invention;

Figure 7 is a perspective view showing a still further modified form of spring clip in accordance with the present invention, wherein the spring clip is formed with a right-angled bend whereby members may be clipped together in right-angular relationship;

Figure 8 is a cross-sectional view taken on line 8—8 of Figure 2.

Referring to the drawings, and more particularly to Figures 1, 2 and 8, 11 designates one form of the spring clip, said clip being formed of a single piece of resilient wire bent to define a pair of symmetrically-disposed, looped portions connected at the lower end of the clip by a horizontal cross-arm 12. Each looped portion comprises a

2

main or vertical inner arm 13 connecting at its one or lower end with one end of right-angled arm element 14 arranged transversely of the arm 13. Designated at 15, 15 are respective inwardly directed intermediate loops and each arranged longitudinally of the adjacent arm 13. The lower or one arm of each intermediate loop 15 connects with the associated other end of arm element 14 and the upper or other arm of each intermediate loop connects with an end of the cross-arm 12. The upper or other arms of the intermediate loops 15, 15 thus define with cross-arm 12 an outer, resilient tongue which may be flexed with respect to the remainder of the spring clip. As shown in Figures 1, 2 and 8, one or more pieces of paper 16, or other flat members, may be secured between the aforesaid resilient tongue and the remainder of the clip.

Connecting with the upper or other end of each vertical arm 13 is an outwardly-directed arm element 17 arranged transversely of each arm 13 and connecting with a loop 18 which is arranged longitudinally of the adjacent arm 13. Each loop 18 terminates in an upwardly and inwardly-directed free spring arm 19 which crosses the loop 18 and also crosses the associated arm element 17. As shown in Figures 1, 2 and 8, one or more pieces of paper 20, or other flat members, may be secured between the spring arms 19, 19 and the remainder of the clip, the lower edges of pieces 20 being received in the loops 18, 18, whereas the upper edges of the pieces 16 are received in the loops 15, 15. In addition, a tape 21 may be secured to the clip in the manner shown in Figures 1, 2 and 8, between arm 12, and the remainder of the lower portion of the clip and between spring arms 19, 19 and the remainder of the upper portion of the clip.

In the embodiment of the invention illustrated in Figure 3, the clip is designated generally at 22. The lower portion of the clip 22 is formed in the same manner as in the embodiment of Figures 1, 2 and 8, and includes a horizontal crossarm 12a, the main or vertical inner arms 13a, 13a, the right angled arm elements 14a, 14a, and the inwardly directed loops 15a, 15a. The vertical inner arms 13a, 13a connect at their top ends with the curving inner arms 23, 23 of respective loops 24, 24. The loops 24, 24 terminate in outer free spring arms 25, 25. The lower portion of clip 22 may be employed in the same manner as the lower portion of clip 11. The upper portion of clip 22 may be employed to secure one or more pieces of paper, or other flat material, between the spring arms 25, 25 and

the remainder of the clip. As shown in Figure 3, one or more tapes 26 may be secured in the loops 24, the arms 25 being formed at their ends with hooks 27 in which the top edges of the tapes may be received.

In the form of the invention of Figure 4, the clip is designated generally at 28 and is similar to clip 22 except that the lower portions of the clip are kidney-shaped rather than rectangular, as shown at 29, 29, and the outer cross-bar portion, designated at 30, is arcuate rather than straight. The top portion of the clip 28 is the same as the top portion of the clip 22.

The kidney-shaped lower portions of the clip enable the clip to be employed as a package-tie device. In tying a package, the string is first wrapped twice around the lower portions of elements 13b, 13b (which are flanked by the comma-shaped members defined by loops 15b, 15b). Then the string is wrapped around the package and is brought back to be again wrapped around said lower portions of the elements 13b, 13b. This securely ties the package without the use of knots. The clips may thus be used in various ways combining the use of string with the holding power of the spring tongues.

In the form of the invention shown in Figure 5, the clip is designated generally at 31. In clip 31 the intermediate inwardly-extending loops, designated at 15', 15' have inner arms 14', 14' which connect with the lower ends of the vertical arms 13c, 13c, and the outer arms of said loops, shown at 32, 32, are connected by a horizontal cross-arm 33 which crosses arms 14', 14' and 13c, 13c, as shown. Arms 32, 32 and 33 thereby define a spring tongue. Pieces of paper or the like may be secured between said spring tongue and the remainder of the clip. The top ends of arms 13c, 13c connect with outwardly-extending arms 34, 34 which are downwardly bent at 35, 35. The vertical arm portions 35, 35 connect with upwardly- and inwardly-directed spring arms 36, 36 which cross the respective arms 34, 34.

In the form of the invention shown in Figure 6, the clip is designated generally at 37. Clip 37 has the inner vertical arms 13d, 13d connecting at their lower ends with upwardly and outwardly-extending loops 38, 38, the outer arms of said loops being connected together at 39. The outer arms of loops 38, 38 define a spring tongue with respect to the remainder of the clip. The top ends of arms 13d, 13d connect with the inner arms of respective downwardly and inwardly-curved loops 40, 40, the outer arms of said loops being defined by an arched member 41. Arched member 41 defines a spring tongue with respect to the remainder of the clip.

In the form of the invention shown in Figure 7, the clip is indicated at 42. Clip 42 comprises inner vertical members 43, 43 connecting with inner horizontal bottom members 44, 44 projecting at right angles to members 43, 43. Connecting with the top ends of vertical members 43, 43 are the outer, downwardly-directed loops 45, 45, the outer arms of loops 45, 45 being defined by the inverted L-shaped spring arms 45, 45. The spring arms 45, 45 define a resilient tongue structure with respect to the top bends 46, 46 connecting arms 43, 43 to loops 44, 44.

Connecting with the outer ends of bottom members 44, 44 are the horizontal, substantially-semi-circular loops 47, 47, the outer arms of said loops being defined by the almost-circular element 48. Member 48 defines a spring tongue

with respect to the remainder of the bottom portion of the clip.

While certain specific embodiments of wire spring clips have been disclosed in the foregoing description, it will be understood that various modifications within the spirit of the invention will occur to those skilled in the art. Therefore, it is intended that no limitations be placed on the invention except as defined by the scope of the appended claims.

What is claimed is:

1. A spring clip formed of wire and comprising a pair of main straight arms disposed in side by side abutting relationship, an inwardly directed loop positioned longitudinally and outwardly of and adjacent to each of said main arms and having one of its arms connected to one end of the adjacent main arm, the other arm of each of said loops forming a resilient tongue adapted to be flexed with respect to said main arms, a second inwardly directed loop positioned longitudinally and outwardly of each of said main arms and adjacent each of said first named loops and each spaced from the adjacent first named loop, each of said second loops having one arm connected to the other end of the adjacent main arm, and together with the other arm of each of said second named loops forming a free spring arm adapted to be flexed with respect to said main arms.

2. A spring clip formed of wire and comprising a pair of main straight arms disposed in side by side abutting relationship, a cross-arm positioned adjacent one end of said main arms, an arm element arranged transversely of each of said main arms adjacent said one end of the main arm and each having one end connected to said one end of the adjacent main arm, an inwardly directed loop positioned longitudinally and outwardly of and adjacent each of said main arms, and having one of its arms connected to the other end of the adjacent arm element, the other arm of each of said loops being connected to and forming with said crossarm a resilient tongue adapted to be flexed with respect to said main arms, and a second inwardly directed loop positioned longitudinally and outwardly of each of said main arms and adjacent each of said first named loops and each spaced from the adjacent first named loop, each of said second loops having one arm connected to the other end of the adjacent main arm, the other arm of each of said second loops forming a free spring arm adapted to be flexed with respect to said main arms.

3. A spring clip formed of wire and comprising a pair of main straight arms disposed in side by side abutting relationship, a crossarm positioned adjacent one end of said main arms, an arm element arranged transversely of each of said main arms adjacent said one end of the main arms and each having one end connected to said one end of the adjacent main arm, an inwardly directed loop positioned longitudinally and outwardly of and adjacent each of said main arms, and having one of its arms connected to the other end of the adjacent arm element, the other arm of each of said loops being connected to and forming with said crossarm a resilient tongue adapted to be flexed with respect to said main arms, a second arm element extending transversely outwardly of each of said main arms at the other end of the main arms and each spaced from said first named arm element adjacent thereto and having one end connected to said other end of the adjacent main arm, and a sec-

ond inwardly directed loop positioned longitudinally and outwardly of each of said main arms and adjacent each of said second arm elements and each spaced from the adjacent first named loop, each of said second loops having one arm connected to the other end of the adjacent second named arm element, the other arm of each of said second loops forming a free arm adapted to be flexed with respect to the adjacent main arm.
